CLAIM

The ornamental design for a ladder for a boat as shown and described.

DESCRIPTION

FIG. 1.1 is a top, front left perspective view of a ladder for a boat embodying my new design;

FIG. 1.2 is a bottom, rear right perspective view thereof;

FIG. 1.3 is a right side elevation view thereof;

FIG. 1.4 is a left side elevation view thereof;

FIG. 1.5 is a front elevation view thereof;

FIG. 1.6 is a rear elevation view thereof;

FIG. 1.7 is a top plan view thereof; and

FIG. 1.8 is a bottom plan view thereof.

FIG. 2.1 is a top, front left perspective view of a second embodiment of a ladder for a boat embodying my new design;

FIG. 2.2 is a bottom, rear right perspective view thereof;

FIG. 2.3 is a right side elevation view thereof;

FIG. 2.4 is a left side elevation view thereof;

FIG. 2.5 is a front elevation view thereof;

FIG. 2.6 is a rear elevation view thereof;

FIG. 2.7 is a top plan view thereof; and

FIG. 2.8 is a bottom plan view thereof.

(Continued)

The broken lines in the figures are included for the purpose of illustrating portions of the ladder for a boat and form no part of the claimed design.
